UNITED STATES PATENT OFFICE.

ANTHONY D. GARGULINSKI, OF WORCESTER, MASSACHUSETTS, ASSIGNOR TO CROMPTON & KNOWLES LOOM WORKS, A CORPORATION OF MASSACHUSETTS.

DROP-BOX-ACTUATING MECHANISM FOR LOOMS.

Application filed December 7, 1921. Serial No. 520,681.

To all whom it may concern:

Be it known that I, ANTHONY D. GARGULINSKI, a citizen of the Republic of Poland, residing at Worcester, in the county 5 of Worcester and State of Massachusetts, have invented a new and useful Drop-Box-Actuating Mechanism for Looms, of which the following is a specification.

This invention relates to mechanism for 10 vertically positioning the shuttle boxes of a drop box loom, and it is the general object of the invention to improve and simplify the mechanism through which the boxes are thus positioned.

15 It is customary in four-box looms to provide two pattern-controlled levers for each set of boxes and to so connect these levers to a drop box lifter rod that four different vertical positions of the rod may be determined by the combination of two operative 20 positions of each lever.

25 My invention relates specifically to an improved construction and combination of parts by which motion may be transmitted from the positioning levers to the lifter rod. Another feature relates to an improved arrangement of giveaway connection between the positioning levers and the lifter rod. Certain features of my invention are also 30 applicable to a two-box loom in which only two different vertical positions of the lifter rod are required. Further features of my invention will be more specifically defined in the appended claims.

35 Preferred forms of my invention are shown in the drawings, in which—

Fig. 1 is a side elevation of portions of a loom with my improved drop box actuating mechanism mounted thereon;

40 Fig. 2 is a detail sectional plan view taken along the line 2—2 in Fig. 1;

Fig. 3 is a side elevation of the yielding link or giveaway connection; for the drop boxes at the right side of the loom;

45 Fig. 4 is a detail front elevation thereof;

Fig. 5 is a partial side elevation showing my invention applied to a loom using only two drop boxes at either end of the lay; and

50 Fig. 6 is a detail front elevation looking in the direction of the arrow 6 in Figs. 1 and 2.

Referring to Figs. 1 to 4, I have shown portions of a loom side 10, a drop box lifter rod 11 and a pair of bell crank positioning levers 12 and 13. The levers 12 and 13 are mounted upon a fixed pivot 14 and are con-

nected by links 15 and 16 to pattern-controlled mechanism of the usual type by which the upper ends of the levers may be shifted forward and rearward as desired.

The parts thus far described are of the 60 usual type and form no part of my present invention.

In order to combine the movements of the levers 12 and 13 to determine the four different vertical positions of the lifter rod 11, 65 I provide a lever 17 which has no fixed center and which may accordingly be designated as a floating lever and which is provided with three bearing or connecting portions 18, 19 and 20. The bearing 18 is pivoted 70 to the forwardly extending arm of the bell crank 13. The end portion 19 has a pin and slot connection with the rearwardly extending arm of the bell crank lever 12 and the end portion 20 has a giveaway link connection with a stud 21 at the lower end of the lifter rod 11. This giveaway link preferably comprises two members 22 and 23 (Fig. 3) pivotally connected near their lower ends and yieldingly connected at their upper ends 75 as by a spring 24. Recesses 25 are formed in the adjacent faces of the members 22 and 23 to receive a stud 26 formed on the end portion 20 of the lever 17.

With these connections, the lifter rod 11 85 will be given four different vertical positions in accordance with the four possible combinations of the two positions of each of the levers 12 and 13. The giveaway link not only permits yielding of the parts in case 90 vertical movement of the shuttle boxes is prevented, but also allows for the necessary swinging movement of the lifter rod with the lay and for the varying transverse position of the end portion 20 as determined by 95 the combination of the positions of the levers 12 and 13.

The connections for the opposite side of the loom are also indicated in the drawings, these connections comprising a second pair 100 of positioning levers 30 and 31, a floating lever 32, a link 33, arms 34 and 35 fixed to a rock shaft 36, and a similar giveaway connection between the arm 35 and the associated lifter rod. The relative proportions of the parts will be found identical although the dimensions are reduced to provide necessary clearance.

It has been found desirable by experiment that the points 18, 19 and 20 should 110

be positioned in a single straight line and that they should be equally spaced. While I do not wish to be limited to this specific arrangement and proportion, it is at present 5 considered the preferred arrangement for this form of my invention.

Certain of the advantages of my invention are of value when used in a loom using 10 two shuttle-boxes at one or both sides of the loom. The construction in this case is somewhat simplified, as will be evident by reference to Fig. 5. In this form of my invention, a lever 40 is mounted on a pivot 41 supported in fixed position by the frame 15 10^a. A single bell crank lever 42 is mounted on a fixed pivot 43 and is connected by a stud 44 to the rear end of the lever 40. The connections from the front end of the lever 40 to the lifter are the same as shown for 20 lever 17 in Fig. 1. The upper end of the bell crank 40 is also similarly connected by a link 45 to an actuating disc not shown.

Provision for the necessary sliding movement of the lever 40 may be made by providing 25 a slot 46 in the lever 42 to receive the pivot stud 44. As the upper end of the lever 42 is moved to forward or rearward position, the shuttle-boxes are shifted to bring either the upper or lower box in line 30 with the picker.

I have also shown in Fig. 5 a second lever 47 pivoted to a stud 48 fixed in the frame 10^a and actuated by a bell crank lever 49 through a sliding connection 50 to move the 35 boxes at the opposite side of the loom by connections similar to those shown in Fig. 1.

The words "directly pivoted" or "directly connected" as used in the claims indicate 40 that the parts thus defined are pivoted or connected directly to each other without the intervention of links or other additional and relatively movable parts.

It will be evident that changes and modifications can be made in my invention with- 45 in the spirit and scope thereof as set forth in the claims, and I do not wish to be otherwise limited to the details herein disclosed but what I claim is:—

1. In a loom, a drop box lifter rod, a pair 50 of positioning levers, a floating lever pivoted directly to one lever and having a direct sliding engagement with the other lever and a connection from said lever to said lifter rod.

2. In a loom, a drop box lifter rod, a pair

of positioning levers having corresponding 55 portions extending in opposite directions, a floating lever directly connected adjacent its center to one positioning lever and adjacent one end the second positioning lever, and a link connecting the other end of said 60 floating lever to said lifter rod.

3. In a loom, a drop box lifter rod, a pair 65 of positioning levers having corresponding portions extending in opposite directions, a floating lever directly pivoted adjacent its 70 center to one of said positioning levers and having a pin and slot connection at one end to the second positioning lever, and a link connecting the other end of said floating lever to said lifter rod.

4. In a loom, a drop box lifter rod, a pair 75 of positioning levers having corresponding portions extending in opposite directions, a floating lever directly pivoted adjacent its center to one of said positioning levers and having a pin and slot connection at one end to the second positioning lever, and a link pivoted to said lifter rod and having a give-way connection to said floating lever.

5. In a loom, a drop box lifter rod, a pair 80 of positioning levers, a floating lever directly and jointly supported by said positioning levers, a link connecting said floating lever to said lifter rod, and selective means to move said positioning levers, the points of 85 pivotal connection of said floating lever to said positioning levers and said link being substantially in a single straight line.

6. In a loom, a drop box lifter rod, a pair 90 of positioning levers, a floating lever direct- 95 ly and jointly supported by said positioning levers, a link connecting said floating lever to said lifter rod, and selective means to move said positioning levers, the points of pivotal connection of said floating lever to 95 said positioning levers and said link being substantially in a single straight line and equally spaced.

7. In a loom, a drop box lifter rod, a po- 100 sitioning lever, a pivotally supported lever having a positive direct connection to said positioning lever at one end, a yielding give-way connection to said lifter rod at the opposite end, and means to move said position- 105 ing lever.

In testimony whereof I have hereunto affixed my signature,

ANTHONY D. GARGULINSKI.
